UNITED STATES PATENT OFFICE.

WILLIAM L. THALER AND HENRY H. GLAZER, OF BROOKLYN, NEW YORK.

KEY CASE.

Application filed June 3 1921. Serial No. 474,674.

To all whom it may concern:

Be it known that we, WILLIAM L. THALER and HENRY H. GLAZER, citizens of the United States, and residents of Brooklyn, in the 5 county of Kings and State of New York, have invented certain new and useful Improvements in Key Cases, of which the following is a specification.

The present invention relates to key-cases 10 in which a group of keys is held movably in a key-case so that they may be applied individually to the key-hole of a lock.

One of the principal objects sought in the 15 key-cases heretofore made, is to confine each key-supporting link to movement in a single plane so that the keys would be held from bunching when turned within the case.

The key-links in such construction have 20 been mounted upon a stationary pivot-rod attached at the ends to the case, and the key-links are so jointed upon this pivot-rod that they are constrained to move in a single plane outside of the case, as well as within, and this greatly restricts their freedom of 25 movement in applying a key to a key-hole and turning it in the lock.

The object of the present invention is to 30 overcome this defect, and to secure entire freedom of movement for the keys when turned outside of the case, thus permitting them to swivel freely in any direction. This greatly promotes the manipulation of the 35 keys in performing their principal function of entering the key-hole and operating the lock.

The body of the case consists of a flexible 40 cover and a stiffening member secured to the inner side of the same at the middle portion, leaving the ends of the cover free to fold over upon the keys.

One of the objects of our invention is to 45 provide such means for stiffening the cover of the case, so that the case when closed is permanently held in flat condition.

Another object of our invention is to provide 50 a suitable connection of the key-supporting element with the end of the stiffening member, to permit each of the individual attaching elements to swivel freely when turned out of the case.

Another object is to provide upon the face 55 of such stiffening member a suitable space in which advertising matter may be applied.

Another object of our invention is to provide 60 our key-case with an identification num-

ber by which its recovery may be effected in case it is lost.

The area of the stiffening member, apart from the connections of the key-supporting elements upon its upper edge, is ample to 60 apply the advertising panel and the identification mark, thus enabling the stiffening member to perform two functions besides the holding of the keys movably in the case, and keeping the case in flat form.

The foregoing and still further objects will be fully apparent from the following description and accompanying drawing forming part of this specification, in which Fig. 1 represents a front view of our key-case in a closed position; Fig. 2 represents the middle portion of our key-case showing the stiffening member and its construction; Fig. 3 represents another form of the key-case in opened position with the suspending 70 elements in their restrained condition within the case; Fig. 4 is a cross sectional view taken on line 4—4 of Fig. 3; Fig. 5 is a detail view of the upper portion of the key-case, illustrating the movement of a key-attaching element when swung out of the case; and Fig. 6 represents a cross sectional view taken on line 6—6 of Fig. 5, showing the manner of attaching the hanger to the key-case.

Referring to the drawing, numeral 10 represents the middle portion of the flexible cover of our key-case which cover extends at 11 and 12 into overlapping flaps, provided with closing means 13 and 14. At 90 the middle portion there is provided a stiffening member 15 which is preferably attached in any convenient manner at its upper and lower portions as indicated at 16, to the middle portion 10 of the cover. This member 15 preferably fits over the entire width of the flexible cover, as shown in the drawing, and thus preserves the form of the key-case permanently.

The stiffening member has a window-like 100 opening 17, within which is provided a transparent sheet 18, as clearly shown in Fig. 4 adapted to cover advertising matter which may be inserted between cover portion 10 and the transparent sheet that may 105 be seen in Fig. 2.

It is obvious that the advertising matter may be applied to the stiffening member in any desired manner.

The lower unperforated portion of the 110

stiffening member may be employed for embossing therein an identification number, which may be registered and by means of which the case may be identified if lost.

5 At the upper edge of the stiffening member, there are provided a series of notches 19 and adjacent perforations 20, which are in alignment with each other so as to provide a guide for the upper portion of the key at-

10 taching elements as shown in Figs. 3 and 4.

This key attaching element is shown in the drawing as a link with a loop 21 at one end to receive the key-head, and a loop 22 at the other end adapted to engage the

15 notches and adjacent perforations of the stiffening member. The perforations are preferably made rectangular so that their sides may snugly engage the edges of the loop 22.

20 The accessible side of the link when turned into the case is formed with the usual snap hook to detachably engage the head of the key, and the rear of the loop 22 is sloped so as to rest within the lower end of the 25 perforation 20 and hold the link from lateral movement when in the case.

The perforations are made of such a length that when the link is slightly raised from the stiffening member it clears the 30 lower end of the perforation, and the link is then free to turn and swivel in any direction, which greatly facilitates the application of a key to a key-hole and turning it 35 therein to operate the lock.

35 When the keys are turned into the case their heads are therefore held in a regular overlapping series, which permits the cover flaps to fold closely about them.

The swiveling of the link is illustrated 40 by the dotted lines shown at opposite sides of the link 21 in Fig. 5, which dotted lines express only two directions in which the link and its attached key may be turned; but all other directions are equally possible with the construction of link described.

45 When the keys are attached and loops 21 are swung into the case, the keys automatically flatten themselves against the stiffening member, whereby the bunching of the keys 50 is effectively prevented. By swinging the key attaching member out of the case and into the position shown in Fig. 5 in solid lines, the key and the key-attaching member may be swiveled in any convenient position when the key is being put into the lock.

55 When the key-attaching elements are swung into the case, their then upper portions are substantially flush with the upper edge of the stiffening member 15. At the 60 middle and upper portion of the stiffening member 15 there is provided a slot 23 for receiving a case hanger, indicated at 24 in Figs. 5 and 6, by means of which the case may be suspended within a pocket or to a 65 belt in a convenient manner.

In the drawing there is shown a preferred form of our stiffening member. It might be stated, however, that various changes may be made therein without departing from the broad scope of our invention. Thus 70 the shape of the stiffening member may vary, the window-like opening may be shifted or take any desired shape or form, or may be in itself of an ornamental nature.

As we intend to use our device mostly for 75 an advertising article, such changes will be unavoidable, and we therefore reserve for ourselves the right to make such changes and improvements arising from the various wants of the purchaser.

80 It will be observed in Fig. 2 that the extension of the stiffening member 15 across the flexible cover affords a considerable space or area for advertising and identification inscriptions below the upper portion of the 85 stiffening member to which portion the key-links are connected.

90 In the drawing, a portion of this area is occupied by the panel or window-like opening 17, and the face of the stiffening member is also provided with the inscription "Identification Number 35632."

95 The provision of such identification number upon the stiffening member enables the latter to perform another function in addition to the mere holding of the keys in the case, and the connection of the advertising member with the stiffening member performs still another function in inducing dealers in various articles to make a gift 100 of the key-case because of its bearing the advertising matter, and inducing the receiver to accept the case because of its bearing the identification number.

105 The stiffening member thus serves three separate functions, first, the carrying of the key-links and keys in the case; second, the display of advertising matter; and third, the display of a registration mark; which functions make the constructive feature of the 110 key-case very desirable for the advertiser, and very useful to the one who receives the case.

115 It will be noticed that our invention differs from others in having notches and perforations in its stiffening plate, and key-links so fitted to them as to form individual loose hinged couplings therewith, and each link adapted to swivel freely in any direction when turned out of the case. Any key 120 in the case may therefore when turned out of the case be handled without any interference from the others, because all the keys fall loosely away from the others when any one of them is grasped to be used in a lock. 125

Having thus set forth the nature of the invention what is claimed herein is:

130 1. A key-case formed with a flexible cover having a stiffening member attached thereto and provided with notches in its upper edge.

- and perforations adjacent thereto, and key-links fitted to the notches and perforations, forming individual loose hinged couplings therewith and engaging the perforations 5 when turned into the case, and swivelling freely in any direction when turned out of the case, as and for the purpose set forth.
2. A key-case having a flexible cover, a flat stiffening member permanently attached 10 to the middle of said cover and adapted to be embraced by the free ends of the said cover, and having a plurality of notches and perforations at the upper end of the stiffening member adapted to receive the key-supporting elements, and an identification inscription applied to said stiffening member.
3. A key-case having a flexible cover, a flat stiffening member permanently attached to the said cover and adapted to be embraced 15 by the free ends of the said cover, the said member having a plurality of notches and perforations at the upper end of the stiffening member provided with key-supporting elements, and the stiffening member being 20 provided with an identification mark and with an advertising panel.
4. A key-case, comprising in combination, a flexible cover, a stiffening member attached thereto at about the middle portion of said 25 cover, a plurality of notches and perforations, aligned with each other, provided at one end of said member and adapted to receive and control the movement of a plurality of key suspending elements engaging 30 said notches and perforations, when said elements are swung into the case, a window-like opening provided in the body of said stiffening member, a transparent sheet also attached to said cover and disposed beneath 35 said opening, and means in said member 40 said opening for receiving a case hanger.
5. In a key-case, a stiffening member, a plurality of inwardly swingable key-supporting elements attached to said member 45 and constructed to swivel freely when swung out of the case and restrained from lateral movement when swung into the case, a slot provided at one end of said stiffening member for receiving a case hanger, a window- 50 like opening in said member, a transparent sheet beneath said opening, said sheet and said stiffening member permanently attached at substantially their four corners to the middle portion of the key-case cover so as 55 to permit the insertion of advertising or similar matter between the case cover and said transparent sheet, and made visible through said window-like opening.
6. In a key-case, a flexible cover, a flat 60 stiffening member provided with an opening, a transparent sheet beneath said opening, said stiffening member and said transparent sheet permanently attached to the middle of said cover and adapted to be em- 65 braced by the free ends of said covers, a plurality of notches and perforations pro- 70 vided at one end of said member, each notch and adjacent perforation being in alignment and adapted to receive a key-supporting ele- 75 ment, and a slot formed at about the middle of the notched and perforated end of said stiffening member for receiving a case hanger.

Signed at New York, in the county of 75
New York and State of New York, this 27th
day of May, A. D. 1921.
